UNITED STATES PATENT OFFICE.

SAMUEL TOLES, OF MOUNT BRYDGES, ONTARIO, CANADA.

EMBEDDED HEEL-PROTECTING PLATE.

No. 921,182.

Specification of Letters Patent.

Patented May 11, 1909.

Application filed October 8, 1908. Serial No. 456,724.

To all whom it may concern:

Be it known that I, SAMUEL TOLES, a citizen of the Dominion of Canada, and resident of Mount Brydges, Ontario, Canada, residing 5 at the present at Effingham, Illinois, have invented certain new and useful Improvements in Embedded Heel-Protecting Plates, of which the following is a specification.

My invention relates to improvements in 10 embedded shoe or boot heel-protecting plates, and the object thereof is to produce a heel-protecting plate which will require the removal of only about one half of the usual slice in the ply of leather in which it is to be 15 embedded, and which is constructed so as to prevent stubbing and so as to interlock with the heel in a manner as to resist retroaction. I attain these objects by the construction illustrated in the accompanying drawing, in 20 which—

Figure 1 is a view of the bottom of a heel provided with my plate; Fig. 2, a section taken on the line X—X of Fig. 1—the plate being in this view in the wearing position; 25 and Fig. 3, an enlarged view in perspective of the plate proper.

Similar letters of reference denote corresponding parts throughout the several views.

My heel-protecting plate is formed segmental in its contour, that its outer end, or periphery, may conform to the periphery, or convexity, of the heel, and right-angular-triangle like in its cross section, that it present a large surface to wear and be amply 35 broad and thick only at the point where it is subject to greater attrition. In consequence of these features of construction the plate wears longer, is lighter in weight, and requires less leather to be removed of the 40 lift in the heel in which it is to be embedded.

In constructing the plate, the surface of the base plane *a* and the periphery *b* are shaped so as to be at right angles to each other; the surface of the base plane *a*, the periphery *b*, and the surface of the top plane *c* thereof, so as to form a right-angular triangle when viewed in side elevation or in cross section. The end *d*, opposite the periphery *b*, is beveled off from the level plane *a* to the inclined plane *c* to a blunt knife edge. In the

inclined surface, or top plane, *c* are formed a plurality of transverse serrations *e*, shaped so as to incline toward the periphery *b*. About in the middle of the breadth and length of the plate thus constructed is a 55 countersunk hole *f*, all as clearly shown in Figs. 2 and 3.

In fitting my plate to the heel *A*, a right-angular-triangle like seat *B* of the proper length and breadth and of a depth corresponding to the thickness of the plate less the height of the serrations *e* and edge of the end *d*, is cut out in the heel at the point requiring reinforcement. The plate is then first driven into the seat *B* laterally, so as to bury 60 the edge of the end *d* in the leather, and then hammered into the seat *B* until the surface of the base *a* is level with the surface of the heel; thereby causing the serrations *e* to impress in the seat *B* corresponding serrations, 65 but inclined in the opposite direction, and thus interlock with the heel. By this means the plate resists the tendency to retrograde under the influence of the friction produced by a shuffling gait of the wearer. A cone-headed nail *C* is then driven into the heel through the hole *f* which nail holds the plate 70 securely in position.

As the leather of the heel wears sooner than the metal of the protecting plate, the 75 edge and corners of the forward end of the plate heretofore caused stubbing, scratching, polished floors or abrading carpets the wearer of the plate walked on. Beveling off 80 the end *d* to an edge and burying the edge in the leather of the heel will effectually prevent stubbing and scratching floors or carpets 85 long after the surface of the heel *B* has begun to wear.

Having described my invention, what I 90 claim is—

1. A heel-protecting plate formed segmental in its contour with the plane of its upper surface inclined toward the plane of its lower surface, its thinner end beveled off from said lower surface toward the plane of said upper surface, and serrations formed in said upper surface inclining toward the thicker end of the plate.
2. A shoe heel having a right-angular-tri- 100

angle like seat with a heel-protecting plate of corresponding formation embedded therein having its thinner end beveled off from its level toward its inclined plane and the beveled off portion embedded in the heel, and inclined serrations in the contactual surfaces of said plate and heel.

In testimony whereof I affix my signature in presence of two witnesses.

SAMUEL TOLES.
